United States Patent Office.

SOLOMON METZGER, OF NEWBERRY, PENNSYLVANIA.

Letters Patent No. 94,123, dated August 24, 1869.

IMPROVEMENT IN VEGETABLE-CUTTERS.

The Schedule referred to in these Letters Patent and making part of the same.

To all whom it may concern:

Be it known that I, SOLOMON METZGER, of Newberry, in the county of Lycoming, and in the State of Pennsylvania, have invented certain new and useful Improvements in Vegetable-Cutters; and do hereby declare that the following is a full, clear, and exact description thereof, reference being had to the accompanying drawing, making a part of this specification, in which—

Figure 1 is a vertical longitudinal section; and

Figure 2 is a plan view of my improved device.

Letters of like name and kind refer to like parts in each of the figures.

My invention has for its object the shredding or slicing of cabbage; and

It consists in the construction and arrangement of the several parts of the device, and also in the employment of a double-edged knife, or cutter, having a reciprocating motion, upon which the cabbage is caused to press by its own weight, by which means a thin shaving or slice of said cabbage is removed at each motion of said cutter.

In the annexed drawing—

A A represent two side pieces, secured together by two cross-pieces, B B, the whole forming the frame of the machine.

Secured to the upper side of said frame is a box or hopper, C, for containing the cabbage, open at both top and bottom, directly beneath which is placed the cutter-head D, its edges being contained within grooves in the inner face of the side pieces, so as to permit said head to slide longitudinally.

A transverse slot or opening, d, is provided in the head, directly above which is placed a double-edged knife or cutter, E, having its edges beyond the sides of said slot, and inclined slightly upward, as shown in fig. 1.

It will be readily seen, that if now a cabbage is

placed within the hopper, and a reciprocating motion given to the cutter-head, at each motion of the same, the forward edge of the cutter will shave off a thin slice from the cabbage, which, passing beneath said cutter, will fall through the slot.

In order to secure the desired motion of the cutter, a crank-shaft, F, is journalled within one end of the frame, and connected with the cutter-head by means of a pitman, G, pivoted at one end to the crank, and at the other end to said cutter-head.

Upon the outer end of said crank-shaft is a pinion, H, which meshes with and is operated by a gear-wheel, I, pivoted upon the side of the frame.

A handle, i, secured to one of the spokes of said gear, permits it to be readily turned by the operator.

As thus constructed and arranged, if a cabbage be placed within the hopper, and the crank turned, said cabbage will be speedily reduced to shreds of a uniform size, the use of said machine causing a great saving of time and labor, and producing a far better result than has heretofore been possible.

Having thus fully set forth the nature and merits of my invention,

What I claim as new, and desire to secure by Letters Patent, is—

The within-described vegetable-cutter, consisting of the frame A A, B and B, the hopper C, the cutter-head D, provided with the slot d and double cutter E, the crank-shaft F, the pitman G, the pinion H, and gear-wheel I, all constructed and arranged to operate substantially as and for the purpose specified.

In testimony that I claim the foregoing, I have hereunto set my hand, this 20th day of July, 1869.

SOLOMON METZGER.
